UNITED STATES PATENT OFFICE.

ALFRED JOHN HEYS AND SAMUEL SALKELD, OF MANCHESTER, COUNTY OF LANCASTER, ENGLAND.

BUTTON OR OTHER FASTENING FOR GARMENTS.

SPECIFICATION forming part of Letters Patent No. 320,061, dated June 16, 1885.

Application filed March 19, 1885. (No model.) Patented in England November 5, 1884, N. 14,616.

To all whom it may concern:

Be it known that we, ALFRED J. HEYS and SAMUEL SALKELD, subjects of the Queen of Great Britain, residing at Manchester, in the county of Lancaster and Kingdom of Great Britain, have invented certain new and useful improvements in Buttons and Similar Attachments or Fastenings for Garments; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of our invention is to provide an improved form of button belonging to the class attachable to garments without the help of tools.

It consists in the details of construction of such buttons; and the nature of the improvements may be discovered in the description below, in connection with the accompanying drawings.

Figure 1 shows a slit disk, which is a part of the button. Fig. 2 is a stud, which is also a part of the button, while Fig. 3 is the button complete.

C is a stud provided with two heads, D and F, of any convenient form and with grooves E and E'.

A is a slit disk having teeth B radiating toward the center, said disk fitting into the groove E upon the stud.

A' is a second slit disk, whose teeth are similar to those of the disk A, and which fit into the groove E', so that the cloth H of the garment is held between the head F and the said slit disk A'. 35

G is a cap covered with cloth and attached to the slit disk A. 40

I am aware that buttons having slit disks have been previously invented, and that said buttons are therefore similar to mine in that respect; but the improved button as a complete article and as a simple and effective and new invention. I claim as follows:

In buttons and similar fastenings for garments, the combination of the following elements: the stud C, provided with the two heads D and F, the slit disk A, fitting into the groove E, the slit disk A', fitting into the groove E', the cap G, secured to said disk A, and the cloth covering M, secured to said disk, substantially as described. 50

In testimony whereof we affix our signatures in presence of two witnesses.

ALFRED JOHN HEYS.
SAMUEL SALKELD.

Witnesses:

JESSE SMITH WELLS,
WILLIAM E. HEYS.
